SPOOL

Filed Dec. 2, 1931

UNITED STATES PATENT OFFICE

GEORGE H. BIRD, OF BROOKLYN, NEW YORK

SPOOL

Application filed December 2, 1931. Serial No. 578,480.

This invention relates in general to spools, and more particularly to that type of spool which comprises a cylindrical tube or core having disks or flanges secured to its ends between which upon the core is wound material to be spooled.

One object of the invention is to provide a novel and improved device for securing the disk or flange upon the end of the tube or core, whereby the disk may be easily and securely fastened to the core and firmly held against both lateral movement and rotation on the core.

Other objects are to provide a device of this character comprising a plate having arms projecting from the outer periphery thereof and at one side at an angle to the plane thereof to be inserted into the end of the tube or core with the plate overlying the outside of the disk, said arms having projections on their outer sides, and a member in engagement with and slidably between the arms longitudinally thereof away from the plate to press the arms into contact with the inner walls of the tube or core and cause said projections to penetrate said tube or core; to provide such a device so constructed that said member may be actuated from one end of the tube or core and shall remain within the tube to positively hold the projections on the arms in the tube; to provide seats on said arms to receive said member and limit movement thereof in all directions; to provide a novel and improved construction and combination of such a fastening device, the disk, and the tube, whereby rotation of the disk relatively of the tube shall be prevented; and to obtain other advantages and results as will be brought out by the following description.

Referring to the accompanying drawing, in which corresponding and like parts are designated throughout the several views by the same reference characters,

Figure 1 is a vertical sectional view, partially in elevation, of the spool embodying my invention;

Figure 2 is an end view of the spool with portions of the fastening device broken away for clearness in illustration;

Figure 3 is a vertical sectional view

through one end of the spool showing the tube, disk and fastening device assembled, prior to the securing of the fastening device in the tube;

Figure 4 is a similar view showing the operation of pressing the arms of the fastening device into contact with the inner walls of the tube to cause penetration of the projections on the arms into the tube;

Figure 5 is a transverse vertical sectional view, on the line 5—5 of Figure 1;

Figure 6 is a plan view of the blank from which the fastening device may be formed;

Figure 7 is a vertical sectional view through one end of a spool, similar to Figure 1, showing a modified form of the fastening device;

Figure 8 is a transverse vertical sectional view, on the line 8—8 of Figure 7;

Figure 9 is a view similar to Figure 7, showing another modification of the fastening device, and

Figure 10 is a detached side elevation of the fastening device shown in Figure 9, before it is inserted into the tube.

Specifically describing the embodiment of the invention illustrated in Figures 1 to 6, inclusive, the reference character 1 designates a cylindrical tube or core, usually made of paper or other fibrous material, and to the ends of which are secured disks or end flanges 2. These disks 2 have central openings 3 of a diameter somewhat less than the internal diameter of the tube 1, and the edges of the opening 3 are notched at 4 to receive the arms of the fastening device about to be described.

This fastening device comprises a plate 5 formed of suitable material, preferably sheet metal, which has a plurality of arms 6 projecting from the outer periphery and at one side thereof at an angle to the plane of the plate. The outer side of each of these arms is formed with one or more tooth-like projections 7. The distance between the opposite arms 6 at their juncture with the plate 5 is slightly greater than the interior diameter of the tube 1, and before the fastening device is inserted into the tube, the arms are preferably inclined inwardly toward each other

85

90

95

100

as shown in Figure 3, so that they may be freely slipped into the tube. A disk-like member 8 having a diameter somewhat less than the internal diameter of the tube 1 is arranged between the arms 6 so as to be slideable longitudinally thereof and in engagement therewith, in the direction away from the plate 5 and toward the free ends of the arms.

- 10 For actuating the member 8, the plate 5 may be formed with a central opening 9 through which may be inserted a tool A which has a reduced end portion B provided with a shoulder C at the inner end of the 15 reduced end portion, and the member 8 may have a central opening 10 of a diameter somewhat greater than the reduced portion B but smaller than the shoulder C, so that when the end portion B of the tool is inserted 20 through the opening 10, the member 8 may be pushed inwardly of the tube.

In assembling the parts, the end disk 2 is placed upon one end of the tube 1 and the fastening device is inserted through the opening 3 in the disk into the end of the tube, as shown in Figure 3, with one arm 6 in each of the notches 4, until the plate abuts the outside of the disk. Then the tool A is inserted through the opening 9 in the plate and 30 into the opening 10 in the member 8, after which pressure is exerted on the tool to force the member 8 longitudinally of the arms 6, as shown in Figure 4. This action presses the arms outwardly into contact with the inner walls of the tube, and eventually causes 35 the projection 7 to penetrate the tube, as shown in Figure 1, so as to prevent the device from pulling out of the tube.

The free ends of the arms are provided 40 with abutments 11 to limit sliding movement of the member 8 toward the ends of the arms, and for preventing movement of the member 8 in the other direction, I may utilize a spring 45 detent 12 in each arm which may be stamped upwardly from the arm. These detents 12 are arranged to be depressed by the member 8 as it is slid toward the free ends of the arms, and to snap inwardly against the side of the member 8 opposite the abutments 11 50 after the member has reached said abutments.

With this construction, it will be observed 55 that the end disk 2 may be easily, quickly and firmly secured to the end of the tube 1 so as to be held against movement relative to the tube in all directions. Rotation of the disk on the tube is prevented by engagement of the notches 4 with the arms 6. To prevent the plate 5 from being pushed inwardly 60 through the opening 3, the plate between the arms 6 is formed with extensions 13 to overlie the outside of the disk 2. To reinforce the plate against bending, the edge of the opening 9 may be formed with a flange 65 14 which may be integral with the plate.

With the arm 6 projecting from the outer periphery of the disc, it is possible to make the arms much longer than would be possible were the arms formed at the inner periphery of the plate; and the arms so located with respect to the plate, cooperate with the plate to greatly reinforce the outer end of the tube 1. If the arms were at the inner periphery of the plate, only the inherent strength of the arms could be relied upon to reinforce the end of the tube. Furthermore, the disk-like member 8 in cooperation with the arms effectually reinforces the tube at an intermediate point in the length of the tube. 70

A modification of the invention is shown in Figures 7 and 8. The construction of this modified form is in general the same as that shown in Figures 1 to 6, inclusive, the difference being that the spring tongues 12 are omitted, and the sides of the arms 15 are formed with inturned flanges 16 which gradually increase in width from the plate toward the free ends of the arms. Adjacent the free ends of the arms the flanges 16 are formed with seats 17 to receive the member 8. 80 The flanges reinforce the arms, and also enable the arms to be forced outwardly at their free ends a greater distance than at their other ends, so that a secure attachment of the fastener device in the tube may be obtained 85 without damaging the end of the tube. 90

This fastening device is used and operated in substantially the same manner as the device shown in Figures 1 to 6, inclusive, the member 8 sliding along the edges of the flanges 16 so as to press the arms 15 outwardly into contact with the walls of the tube until the member 8 reaches the seats 17, whereupon the member snaps into said seats and is held against further movement 105 in all directions. The arms 15 are provided with suitable projections 19 corresponding to the projections 7 for securing the fastening device in the tube.

Another modification is shown in Figures 110 9 and 10 of the drawing, wherein the flanges 20 corresponding to the flanges 16 have portions 21 adjacent their outer ends of a uniform width throughout their length.

With this form of the invention, the member 8 is slid along the edges of the flanges 20, constantly pressing the arms 22 outwardly in contact with the inner wall of the tube, until the member reaches the portions 21 of the flanges, whereupon outward movement of 120 the arms stops. This construction has advantages over the construction shown in Figures 7 and 8, in that there is no tendency of the arms 22 to spring inwardly after the member 8 has reached the seats 21, as is the 125 case when the member 8 reaches the seats 17. Such inward swinging of the arms after they have been pressed outwardly to the limit, tends to withdraw the projections 19 from the tube and induce some looseness, although 130

not enough looseness to interfere with the secure attachment of the fastening device to the tube.

For limiting movement of the member 8 toward the free ends of the arms 22, abutments 23 may be formed at the outer ends of the portions 21 of the flange, and to prevent movement of the member 8 in the opposite direction, a spring detent 24 like the detent 12, 10 may be provided in each arm 22 to engage the side of the member 8 opposite the abutments 23. As the member 8 slides toward the free ends of the arms 22, it depresses the detents 24 and slides thereover, and after the 15 member 8 has passed the detents, they snap outwardly, as shown in Figure 9.

While I have shown my invention as embodied in several different forms and in different details of construction, it should be understood that this is primarily for the purpose of illustrating the principles of the invention, and that the details of construction may be further modified or changed by those skilled in the art without departing from the 25 spirit or scope of the invention.

Having thus described the invention, what I claim is:

1. A spool comprising a tube, an end flange therefor having a central opening to register with one end of said tube, and a fastening device for securing said flange on said tube including a plate overlying the outside of said flange around said opening and having integral arms projecting from its outer periphery at an angle to the plane of said plate and formed with outwardly extending projections, said arms extending through said opening in said flange into said tube, and a member between and engaging said arms which has been slid longitudinally thereof from said plate toward the free ends of said arms so as to press said arms outwardly into contact with the inner walls of the tube to cause said projections to penetrate said tube.

45 2. A spool comprising a tube, an end flange therefor having a central opening to register with one end of said tube, and a fastening device for securing said flange on said tube including a plate overlying the outside of said flange around said opening and having integral arms projecting from its outer periphery at an angle to the plane of said plate and formed with outwardly extending projections, said arms extending through said opening in said flange into said tube, and a member between and engaging said arms which has been slid longitudinally thereof from said plate toward the free ends of said arms so as to press said arms outwardly into contact with the inner walls of the tube to cause said projections to penetrate said tube, said arms having abutments to limit sliding of said member toward the ends of the arms.

3. A spool comprising a tube, an end flange therefor having a central opening to regis-

ter with one end of said tube, and a fastening device for securing said flange on said tube including a plate overlying the outside of said flange around said opening and having integral arms projecting from its outer periphery at an angle to the plane of said plate and formed with outwardly extending projections, said arms extending through said opening in said flange into said tube, and a member between and engaging said arms which has been slid longitudinally thereof from said plate toward the free ends of said arms so as to press said arms outwardly into contact with the inner walls of the tube to cause said projections to penetrate said tube, said arms having seats to receive said member for limiting movement thereof toward the ends of the arms and holding said member against movement in the other direction.

4. A spool comprising a tube, an end flange therefor having a central opening to register with one end of said tube, and a fastening device for securing said flange on said tube including a plate overlying the outside of said flange around said opening and having integral arms projecting from its outer periphery at an angle to the plane of said plate and formed with outwardly extending projections, said arms extending through said opening in said flange into said tube, a member between and engaging said arms which has been slid longitudinally thereof from said plate toward the free ends of said arms so as to press said arms outwardly into contact with the inner walls of the tube to cause said projections to penetrate said tube, said arms having abutments to limit sliding of said member toward the ends of the arms, and a spring detent to prevent movement of said member in the other direction.

5. A spool comprising a tube, an end flange therefor having a central opening to register with one end of said tube, and a fastening device for securing said flange on said tube including a plate overlying the outside of said flange around said opening and having integral arms projecting from its outer periphery at an angle to the plane of said plate and formed with outwardly extending projections, said arms extending through said opening in said flange into said tube and having inturned side flanges gradually increasing in width from said plate toward the free ends of said arms, and a member which has been slid along said flanges in engagement therewith between said arms longitudinally thereof away from said plate so as to press said arms outwardly into contact with the inner walls of said tube and cause said projections to penetrate the tube.

6. A spool comprising a tube, an end flange therefor having a central opening to register with one end of said tube, and a fastening device for securing said flange on said tube including a plate overlying the outside,

of said flange around said opening and having integral arms projecting from its outer periphery at an angle to the plane of said plate and formed with outwardly extending projections, said arms extending through said opening in said flange into said tube and having inturned side flanges gradually increasing in width from said plate toward the free ends of said arms, a member which has been slid along said flanges in engagement therewith between said arms longitudinally thereof away from said plate so as to press said arms outwardly into contact with the inner walls of said tube and cause said projections to penetrate the tube, said arms having abutments to limit movement of said member toward the ends of said arms, and a spring detent to prevent movement of said member in the other direction.

20 7. A spool comprising a tube, an end flange therefor having a central opening to register with one end of said tube, and a fastening device for securing said flange on said tube including a plate overlying the outside of said flange around said opening and having integral arms projecting from its outer periphery at an angle to the plane of said plate and formed withoutwardly extending projections, said arms extending through said opening in said flange into said tube and having inturned side flanges gradually increasing in width from said plate toward the free ends of said arms, and a member which has been slid along said flanges in engagement therewith between said arms longitudinally thereof away from said plate so as to press said arms outwardly into contact with the inner walls of said tube and cause said projections to penetrate the tube, said flanges having seats to receive said member for limiting movement thereof toward the ends of the arms and holding said member against movement in the other direction.

45 8. A spool comprising a tube, an end flange therefor having a central opening to register with one end of said tube, and a fastening device for securing said flange on said tube including a plate overlying the outside of said flange around said opening and having integral arms projecting from its outer periphery at an angle to the plane of said plate and formed with outwardly extending projections, said arms extending through said opening in said flange into said tube and having inturned side flanges gradually increasing in width from said plate toward the free ends of said arms, a member which has been slid along said flanges in engagement therewith between said arms longitudinally thereof away from said plate so as to press said arms outwardly into contact with the inner walls of said tube and cause said projections to penetrate the tube, each of said flanges having a portion at its outer end of substantially uniform width through-

out its length to form a seat for said member, and an abutment to limit movement of said member toward the ends of said arms beyond said seat.

9. A spool comprising a tube, an end flange therefor having a central opening to register with one end of said tube, and a fastening device for securing said flange on said tube including a plate overlying the outside of said flange around said opening and having integral arms projecting from its outer periphery at an angle to the plane of said plate and formed with outwardly extending projections, said arms extending through said opening in said flange into said tube and having inturned side flanges gradually increasing in width from said plate toward the free ends of said arms, a member which has been slid along said flanges in engagement therewith between said arms longitudinally thereof away from said plate so as to press said arms outwardly into contact with the inner walls of said tube and cause said projections to penetrate the tube, each of said flanges having a portion at its outer end of substantially uniform width throughout its length to form a seat for said member, an abutment to limit movement of said member toward the ends of said arms beyond said seat, and a spring detent to limit movement of said member from said seat in the other direction.

10. A spool comprising a tube, an end flange therefor having a central opening to register with one end of said tube, and a fastening device for securing said flange on said tube including a plate overlying the outside of said flange around said opening and having integral arms projecting from its outer periphery at an angle to the plane of said plate and formed with outwardly extending projections, said arms extending through said opening in said flange into said tube, and a member between and engaging said arms which has been slid longitudinally thereof from said plate toward the free ends of said arms so as to press said arms outwardly into contact with the inner walls of the tube to cause said projections to penetrate said tube, the opening in said disk being smaller in diameter than the inside of said tube and having notches in its edges to receive said arms so as to hold said disk against rotation relatively to said tube. 100 105 110 115 120

11. The spool set forth in claim 1, wherein said plate has a central opening and said member has a central opening of smaller diameter whereby a tool having a diameter smaller than the opening in said plate and greater than the opening in said member and having a reduced end smaller than said opening in said member, may be inserted through the opening in said plate to bring said reduced end into said opening in said 125 130

member and slide said member along said arms.

12. A device of the character described, comprising a plate having a plurality of 5 integral arms projecting from its outer periphery at one side of the plate and at an angle to the plane thereof, said arms being spaced substantially equidistantly from the axis of the plate and having projections on 10 their outer sides, a member between and in engagement with said arms and slidably longitudinally thereof from said plate to press said arms outwardly, and seats at the ends of said arms to receive said member and 15 limit sliding movement thereof in all directions.
